UNITED STATES PATENT OFFICE

MELVILLE M. WHEELER, OF NASHVILLE, TENNESSEE

DESIGN FOR A CORNER VANITY DRESSER

Application filed July 14, 1932. Serial No. 44,329. Term of patent 14 years.

To all whom it may concern:

Be it known that I, MELVILLE M. WHEELER, a citizen of the United States, residing at Nashville, in the county of Davidson and State of Tennessee, have invented a new, original, and ornamental Design for Corner Vanity Dresser, of which the following is a specification, reference being had to the accompanying drawing, forming part thereof.

Fig. 1 is a perspective view; and

Fig. 2 is a plan view of a corner vanity dresser embodying my new design.

I claim:

The ornamental design of a corner vanity dresser, as shown.

MELVILLE M. WHEELER.
